CONTROL SYSTEM

Llewellyn C. Hardesty, Scotia, N. Y., assignor to
 General Electric Company, a corporation of
 New York

Application March 1, 1933, Serial No. 659,057

7 Claims. (Cl. 103—25)

This invention relates to control systems, more particularly to fluid control systems, and it has for an object the provision of a simple, reliable, and efficient system of this character.

The invention is illustrated in one form thereof as embodied in a fluid control system in which the fluid is circulated by means of a motor driven pump. In carrying the invention into effect in one form thereof, means are provided for starting the pump motor, and means are also provided for stopping the pump motor if fluid does not start to flow within a predetermined time interval after starting the pump together with means for preventing the restarting of the pump for a predetermined time interval.

For a better and more complete understanding of the invention reference should now be had to the following specification and to the accompanying drawing the single figure of which is a simple diagrammatical sketch of an embodiment of the invention.

Referring now to the drawing, a fluid, such for example as water, is circulated by means of a pump through a fluid system illustrated in the drawing by the pipe 11 and the surge tank 12. The pump is driven by any suitable driving means such for example as that represented by the electric motor 13, illustrated as an alternating current type motor supplied from a suitable source represented in the drawing by the three supply lines 14 to which the motor terminals are connected by means of the three conductors 15. The starting and acceleration of the motor 13 are controlled by primary resistance sections 16, 17, 18 and 19 which in turn are under the control of suitable switching apparatus illustrated as comprising accelerating contactors 20, 21, and 22 and a line contactor 23.

A pressure governor 24, responsive to changes in fluid pressure within the surge tank 12, serves to control the starting and stopping of the motor 13 automatically, while suitable manually operated control devices illustrated as a switching device 25 with normally open contacts and a switching device 26 with normally closed contacts serve respectively to start and stop the motor. Suitable means 27 illustrated as a switching device serves to transfer the control from hand to automatic and vice versa. When the switching device 27 is in the position in which it is illustrated, the starting and stopping of the motor is under the control of the manually operated start and stop push-buttons 25 and 26, whilst when the device 27 is operated to its other position, the starting and stopping of the motor is under the control of the pressure governor 24.

In order to prevent water hammer or other undesirable operating conditions in a fluid circulating system likely to arise if the fluid does

not start to circulate within a predetermined interval of time after the pump 10 has started, the line contactor 23 is provided with a time element device 28 which cooperates with an auxiliary interlock on the first accelerating contactor 20 and with a control relay 30 to stop the pump motor if fluid does not start flowing within a predetermined time after the pump is started. A "no flow" device 31 illustrated as a fluid flow responsive relay cooperates with a control relay 32 to prevent the time element device 28 and the interlock 20, from stopping the motor 13 if fluid starts to flow in the pipe 11 within the time interval determined by the setting of the time element device 28. A time element device 33 serves to prevent restarting of the pump within a predetermined time interval after the operation of the time element device 28 and interlock 20, to stop the pump motor. For the purpose of rendering the "no flow" device 31 ineffective if desired, a switching device 34 is provided. This switching device has two positions; an upper position in which the contacts of the relay 30 controlled by the "no flow" device 31 are short circuited and a lower position in which the contacts of the "no flow" device 31 are connected to one side of the supply source. A clock switch 36, illustrated as comprising a small self-starting synchronous motor 37 and a movable contact member 38 driven thereby, serves to render the controlling apparatus effective for certain hours of the day and ineffective for the remaining hours of the day. If it is desired to operate the system at a time when the controlling apparatus is rendered ineffective by the position of the contact of the clock switch, a manually operated switching device 37a is provided for short circuiting the contacts of the clock switch.

With the above understanding of the elements and apparatus and their organization in the completed system the operation of the system itself will readily be understood from the following detailed description:

Assuming that automatic operation of the system is desired, the switch 27 is operated to the automatic position in which its movable contact member 27a is in contact with its cooperating stationary contact members 27b and in which its left-hand movable contact member 27c bridges the cooperating upper stationary contacts 27d. Further assuming that it is desired to render the "no flow" device 31 effective, the movable contact of switching device 34 is operated into engagement with its lower cooperating stationary contact members 34a. At some predetermined time of day the movable contact members 38 of the clock switch 36 are operated into engagement with the pawl of the contact arm 40, which is connected by means of a spring with another contact arm 41, thereby constituting an over-center

switch. As the contact 38 engages the pawl of contact 40, the latter is operated into engagement with stationary contact 42.

If the fluid pressure in the surge tank drops below some predetermined value, the piston 24, of the pressure governor 24 descends from its upper to its lower position, thereby snapping the contact arm 43 into engagement with the stationary contact 44 to complete an energizing circuit for the operating coil of the pressure governor relay 45, which circuit is traced from the lower supply line 14 through the right-hand contact of the manually operated switch 46, through conductor 47, contacts 40 and 42 of the clock switch 36, conductors 48 and 50, contacts of control relay 30 in the closed position thereof, conductor 51, contacts 27_c and 27_d of the transfer switch, conductors 52 and 53, contacts 43 and 44 of the pressure governor, conductor 54, operating

coil of pressure governor relay, and thence by resistance 55 and conductor 56 to the left-hand side of switch 46 and thence to the upper supply line 14. Relay 45, in responding to the energization of its operating coil, closes its contacts.

The upper contact of the relay establishes a holding circuit for the coil independently of the contacts 43 and 44, which circuit is traced from the lower supply line 14 to the conductor 53 as before, thence through the upper contact of the

relay, operating coil of the relay and thence by conductor 56 and switch 46 to the upper supply line as before.

The lower contact of the pressure governor relay 45 establishes an energizing circuit for the operating coil of accelerating contactor 20 that is traced from the lower supply line 14 to the conductor 53 as before, then through the lower contact of the pressure governor relay, conductor 57, contacts 27_a and 27_b of the transfer switch,

conductor 58, operating coil of accelerating contactor 20, thence by conductor 60 to and through the normally closed interlock 23_a of the line contactor 23 and thence by conductor 61 to and through the left-hand side of switch 46 of the

upper supply line 14. Accelerating contactor 20 closes in response to the energization of its operating coil thereby connecting the terminals of the pump motor 13 to the supply line 14 (assuming the prior closure of manually operated switch

62) with resistance sections 16, 17 and 18 in circuit therewith. The motor 13 is now energized and starts to rotate at slow speed.

After an interval of time determined by the setting of the time element device 63 the closing of contactor 20 actuates the movable contact member 63_a into engagement with its cooperating stationary contact 63_b, thereby completing an energizing circuit for the operating coil of accelerating contactor 21, which circuit is traced from

the lower supply line 14 to the conductor 58 as previously traced, contacts 63_a and 63_b, thence by conductor 64 to and through the operating coil of accelerating contactor 21 and thence by conductor 60 to the upper supply line 14, as previously traced.

Contactor 21 closes in response to the energization of its operating coil, short circuiting the resistance section 18 and increasing the speed of the motor 13, as is well understood. In a similar manner, accelerating contactor 22 is

70 energized and closed to short circuit the resistance section 17 after an interval of time determined by the setting of time element device 65, and finally the line contactor 23 is similarly energized and closed to short circuit the resistance

75 section 16 after an interval of time determined

by the setting of time element device 66. Line contactor 23 in responding to the energization of its operating coil closes its main contacts and short circuits the resistance section 16 thereby connecting the terminals of the motor 13 directly to the line 14 as a result of which the motor now operates at full speed. Simultaneously, contactor 23 disengages its movable interlock contact member 23_a from engagement with lower stationary contact 23_b thereby interrupting the energizing circuits for the operating coils of accelerating contactors 20, 21 and 22 which energizing circuits were previously traced through the interlock 23_a. As a result, contactors 20, 21 and 22 are deenergized and descend into the lower open positions in which they are illustrated in the drawings. Contact 20, in opening, causes interlock contact 20_a to engage its lower cooperating stationary contact members.

If fluid starts to flow in the line 11, the vane 95 of the no flow device 31 is actuated into engagement with its cooperating stationary contact members 31_a in response to the rising pressure in the line. The bridging of the contacts 31_a establishes an energizing circuit for the operating coil 100 of control relay 32 which circuit is traced from the lower supply line 14 to the conductor 50, as previously traced, and then through contacts 34 and 34_a thence by conductor 67, contacts 31_a (bridged by the movable contact of the no flow device 31) 105 conductor 68, operating coil of control relay 32 and thence by conductor 61 to the upper supply line 14 as previously traced. Control relay 32 in responding to the energization of its operating coil disengages its movable contact member from 110 engagement with its stationary contacts and thereby prevents the time element interlock 28 from completing an energizing circuit for the operating coil of control relay 30. However, if fluid has not started to flow within an interval 115 of time after the closing operation of the line contactor 23, which interval of time is determined by the setting of the time element device 28, an energizing circuit is established for the operating coil of control relay 30. This circuit 120 is traced from the lower supply line 14 to the conductor 67, as previously traced, thence by conductor 70, to and through interlock 20_a (in the lower position thereof), conductor 71, contact 28_a (bridged by the movable contact member of 125 time element device 28 in response to the closing operation of line contactor 23) thence by conductor 72, contacts of relay 32 in the closed position thereof, conductor 73, movable contact 74 of time element device 33, stationary contact 75, 130 conductor 76, operating coil of relay 30, and thence by conductor 61 to the upper supply line 14 as previously traced.

Control relay 30 in responding to the energization of its operating coil disengages its movable 135 contact member from engagement with its stationary contact members, thereby opening the energizing circuit for the operating coil of the line contactor 23, as well as the energizing circuit for the operating coils of the accelerating contactors 140 20, 21 and 22 which energizing circuits were all previously traced through the contacts of control relay 30. The interruption of the energizing circuit of line contactor 23 causes the latter to be deenergized and to descend to its lower open position in which it disconnects the motor 13 from the source 14, thereby shutting down the pump 10. Contact 23 in opening also causes the movable contact member of the time element interlock 28 to be disengaged from its stationary contact 150

members 28a, thereby interrupting the energizing circuit previously traced through these contacts for the operating coil of the control relay 30. If control relay 30 were to become deenergized and allowed to reclose its contact, it would be possible for the pressure governor 24 to restart the apparatus in the previously described manner. This, however, would cause water hammer, or other undesirable operating conditions in the line 11 and is prevented by operation of the time element device 33.

When the contacts 28a of the time element interlock 28 were bridged to complete the energizing circuit for the operating coil of relay 30, an energizing circuit was also completed for the operating coil 77 of the time element device 33. This energizing circuit is traced from the lower supply line 14 to the conductor 73, as previously traced, thence through the operating coil 77 and by conductors 78 and 61 and switch 46 to the upper supply line 14. Energization of the operating coil 77 attracts movable contact 80 into engagement with its cooperating stationary contact 81, thereby completing a holding circuit for the operating coil of control relay 30 independently of the stationary contact 28a of the time element interlock 28, which holding circuit is traced from the lower supply line 14 to the conductor 71 as previously traced, thence by conductor 82, contacts 81 and 80, contacts 74 and 75, conductor 76, operating coil of control relay 30, and thence by conductor 61 to the upper supply line 14 as previously traced. It will also be clear that a holding circuit is established for the operating coil 77 that is traced from the lower supply line 14 to the conductor 71 as before and thence by conductor 82, contacts 81 and 80, coil 77 and thence by conductors 78 and 61 to the upper supply line 14. As contact 80 is drawn into engagement with its stationary contact 81, the L-shaped member 83 is rotated about a pivot 84 in a clockwise direction. The shaft 85, one extremity of which is journaled in the L-shaped member 83, is allowed to descend thereby moving the worm 86 into engagement with wormwheel 87. At the same time the hook member 88, which is attached to the movable contact member 80, engages the upper extremity of contact 74, thereby biasing the latter in a clockwise direction. Contact 74, however, is prevented from clockwise rotation by the pawl at the left-hand end of the lever 90. The closing of contacts 80 and 81 also completes a circuit for the operating coil of the disc motor 91, which circuit is traced in the lower supply line 14 to the conductor 82 as before, thence through contacts 81 and 80, contacts 74 and 75, conductor 76, operating coil of disc motor 91 and thence by conductors 78 and 61 to the upper supply line 14.

It will be clear that the operating coil of the control relay 30 is in parallel with the operating coil of the disc motor 91, and consequently as long as the latter is energized the control relay 30 is also energized and its movable contact member is held in its upper open position thereby preventing the system from being restarted. The disc motor 91 rotates the worm 86 and likewise the wormwheel 87 in a clockwise direction and at a speed that is preferably substantially constant. As shown in the drawing, the wormwheel 87 is provided with a pin 87a. After a predetermined interval of time this pin engages the right-hand extremity of the lever 90 thereby rotating the latter in a counter-clockwise direction about the pivot 90a. This counter-clockwise rotation of the lever 90 disengages the pawl from the contact

member 74 which, as previously stated, is biased for clockwise rotation by the hook 88. Thus as the pawl of the lever 90 is disengaged from the contact 74, the latter is disengaged from the movable contact 75, thereby interrupting the energizing circuit for the operating coil of the disc motor 91 previously traced through contacts 74 and 75. As a result, the rotation of the disc motor 91 is stopped and since the coil of control relay 30 is in parallel with the operating coil of the motor, the relay is likewise deenergized and its movable contact member is allowed to descend into engagement with its cooperating stationary contact, thereby leaving the control system in a reset condition. The pump motor 13 is now restarted in the previously described manner. It will thus be seen that if fluid does not start to flow in the line 11 within a predetermined interval of time after the closing of the line contactor, the pump motor 13 is shut down and cannot be restarted for a predetermined interval of time, determined by the time element device 33.

However, if fluid starts to flow in the line 11 within the predetermined time interval, the pump is not shut down, but continues to operate until sufficient pressure is built up in the surge tank 12 to cause the pressure governor 24 to operate its movable contact member 43 into engagement with the upper stationary contact member 43a short circuiting the coil of the pressure governor relay 45. This short circuiting of the coil of the pressure governor relay causes the latter to open its contact and interrupt the energizing circuit of the line contactor 23 previously traced through the lower contact of the pressure governor relay. The line contactor 23 opens its contact in response to the interruption of its energizing circuit and disconnects the pump motor 13 from the supply source 14, thereby shutting down the pump.

A subsequent drop in the fluid pressure within the surge tank causes the above described operation to be repeated.

If manually controlled operation is desired instead of automatic operation, the transfer switch 27 is operated to the position in which it is illustrated in the drawing. To start the pump motor 13 the start button 25 is operated to the closed position in which it completes an energizing circuit for the operating coil of the pressure governor relay 45, which circuit is traced in the lower supply line 14, through the right-hand contact of switch 46, conductors 47 and 48, contacts of control relay 30, conductor 51, contact 27a and lower stationary contacts of the transfer switch, conductor 94, normally closed contacts of stop button 26, intermediate and right-hand stationary contacts of start button 25 bridged by the movable contact member, conductor 95, operating coil of pressure governor relay 45 and thence by conductor 56 to the upper supply line 14. Simultaneously an energizing circuit is completed for the operating coil of accelerating contactor 20, this circuit being traced from the lower supply line 14 to the start button 25 as before, and thence by conductor 58 to and through the operating coil of contactor 20, and thence by conductor 60, normally closed interlock contacts 23a, 23b, and conductor 61 to the upper supply line 14. Contactor 20 closes in response to the energization of its operating coil and its interlocking contact 20a completes a holding circuit independently of the start button 25. This circuit is traced from the lower supply line 14 through the stop button 26 as before, thence by conductor 53, lower contact of pressure governor relay 45, conductor 57, 150

- upper contacts of transfer switch bridged by movable contact 27, conductors 96 and 97, upper auxiliary stationary contact 20_b bridged by the movable contact 20_a and thence by conductor 60 to the upper supply line 14 as previously traced. It is also clear at this point that the pressure governor relay 45 establishes a self holding circuit for its own operating coil traced from the lower supply line 14 to the stop button 26 as before, thence by conductor 53 to and through the upper contact of pressure governor relay 45, through the operating coil of the pressure governor relay and thence by conductor 56 to the upper supply line 14. Since self holding circuits 15 are established both for the pressure governor relay 45 and the accelerating contactor 20 independently of the start button 25, the latter may now be released and the operation from this point on is identical with the previously described automatic operation.
- If it is desired to dispense with the control usually effected by the no flow device 31, the switch 34 is operated into an engagement with its upper stationary contacts thereby preventing energization and operation of the control relays 30 and 32 to shut down the pump motor 13.
- Although in accordance with the provisions of the patent statutes this invention is described as embodied in specific apparatus, it will be understood that the elements and apparatus shown in the drawing and described in the specification are merely illustrative and that the invention is not limited thereto since alterations and modifications will readily suggest themselves to persons skilled in the art without departing from the true spirit of this invention or the scope of the annexed claims.
- What I claim as new and desire to secure by Letters Patent of the United States is:
1. In a fluid pump control system, a pump, means responsive to a pressure condition in said system for starting said pump, means responsive to the flow of fluid through said pump for stopping said pump upon failure of fluid to flow within a predetermined interval of time after said pump is started, and means for preventing the restarting of said pump for a predetermined interval of time after said pump is stopped.
  2. In a fluid control system for pumps and the like, a motor for driving the pump, means responsive to a pressure condition in said fluid system for starting said motor, means responsive to fluid flow and a time element device cooperating therewith for stopping said motor upon failure of fluid to flow within a predetermined time after the starting of said motor, and means including a second time element device for preventing restarting of said driving means for a predetermined interval of time.
  3. In a fluid pump control system, a pump, a motor for driving said pump, switching means for controlling the starting and stopping of said motor, means for actuating said switching means to start said motor, a control device responsive to said actuation of said switching means for actuating said switching means to stop said motor, a time element device responsive to each stopping of said motor for preventing restarting for a predetermined interval of time thereafter and means responsive to flow in said system for rendering said control device inactive to stop said motor.
4. A fluid flow control system for a pump comprising a motor for driving the pump, switching means for controlling said motor, means for actuating said switching means to start said motor, means for actuating said switching means to stop said motor upon failure of fluid to flow within a predetermined interval of time after starting said motor comprising a device controlled by the fluid pressure and a time element device actuated by said switching means and cooperating with said pressure controlled device, and a second time element device actuated by said first time element device for preventing restarting of said motor within a predetermined interval of time. 80
5. A fluid pump control system comprising a motor for driving the pump, means for controlling the supply to said motor comprising switching apparatus provided with an energizing circuit, means for completing said circuit and actuating said switching apparatus to start said motor, means for interrupting said circuit to stop said motor comprising a time element device actuated by said switching apparatus, a second time element device controlled by said first time element device for preventing restarting of said motor within a predetermined time interval after said motor is stopped, and means responsive to flow of fluid for rendering said first time element device ineffective. 85
6. A fluid pump control system comprising a motor for driving the pump, means for controlling the supply to said motor comprising switching apparatus provided with an energizing circuit, a relay for controlling said circuit, means for completing said circuit and actuating said switching apparatus to start said motor, a time element device actuated by said switching apparatus for causing said relay to interrupt said energizing circuit and stop said motor, a fluid pressure device and a relay controlled thereby for rendering said time element device ineffective to stop said motor if the fluid starts to flow, and a second time element device actuated by said first time element device for preventing restarting of said motor within a predetermined time interval. 90
7. A fluid pump control system comprising a motor for driving the pump, speed controlling resistance connected in circuit with said motor, an accelerating switch and a line switch for controlling said resistance, said switches being provided with energizing circuits, said line switch being provided with an auxiliary contact for interrupting the energizing circuit of said accelerating switch when said line switch is closed, a device responsive to a change in fluid pressure for completing said energizing circuits to start said motor, a relay for controlling said energizing circuits, a time element device actuated by the closing of said line switch and a contact actuated by the opening of said accelerating switch for actuating said relay to interrupt said energizing circuits and stop said motor, a fluid pressure device and a second relay controlled thereby for preventing said first relay from stopping said motor if fluid starts to flow, and a second time element device actuated by said first time element device and said contact for preventing restarting of said motor for a predetermined interval of time. 100

LLEWELLYN C. HARDESTY.
